PUMP CONTROL SYSTEM

Richard H. Cole, Crystal, Minn., assignor to Minneapolis-Honeywell Regulator Company, Minneapolis, Minn., a corporation of Delaware

Filed Dec. 16, 1960, Ser. No. 76,281
7 Claims. (Cl. 60—52)

The present invention is directed to an arrangement of pumps wherein a small control signal is all that is required to control a substantial pumping pressure. More specifically, the present invention is directed to a pair of electromagnetic conductive fluid pumps which are placed in series opposition to one another so that the first pump, which is of a low pressure output, can control the fluid supplied to the second, or power pump.

In the art of pumping various fluids, it becomes desirable in certain cases to be able to either modulate the flow of fluid in response to a signal, or to be able to completely cutoff the flow of fluid after a specific volume has been pumped or delivered. In most conventional pumping systems the modulation or control can be accomplished readily by installing control devices such as ordinary valves or by using variable control pumps. The conventional approaches to control of pumped fluids are not readily adapted to control of conductive fluids of the liquid metal types. The various conductive fluids such as mercury, sodium, potassium, or a sodium-potassium mixture, are of corrosive and poisonous natures and are quite difficult to handle unless a hermetically sealed system is involved. In order to control a hermetically sealed system, ordinary valving becomes difficult due to the sealing problems and also due to the corrosive action of the conduction fluids on various members of a valve that may be attempted for use.

In conductive fluids systems that utilize electromagnetic conductive fluid pumps of the Faraday type, there are no obstructions in the pumping channel which prevent reverse flow when the pump is deenergized. In order to hold a system using this type pump at a particular level, the electromagnetic conductive fluid pump either must be continuously energized at a fixed level or some type of mechanical valving inserted to close the system upon de-energization of the pump. The present invention is directed to a unique control system that utilizes two electromagnetic conductive fluid pumps in series opposition. The first pump, which is a low pressure pump, can be adapted to cut off the flow of fluid to a second or high pressure pump. With this arrangement it is possible to utilize a very small control signal to in turn control a power pump capable of developing a rather high pressure. With the arrangement disclosed it is possible to either obtain "off"-on" control or a step modulated type control. The use of the present invention is particularly adapted for modulation of an electromagnetic conductive fluid pump and actuator of the type disclosed in the United States Patent No. 2,948,118. This will be brought out more fully in the description of the present invention in the body of the specification.

It is thus the primary object of the present invention to disclose a fluid control system utilizing two pumps in opposition so that the first pump, with a low pressure output and low control signal, can handle the control function in a system that utilizes a power pump developing a high pressure and utilizing a substantially greater amount of input power.

It is a further object of the present invention to disclose a fluid control system for electromagnetic conductive fluid pumps that have normally unobstructed, open passages therethrough.

It is yet a further object of the present invention to disclose a pump control system of a modulating type

2

wherein the control power required is small compared to the power required to operate or modulate the main fluid pump alone.

Still a further object of the present invention is to disclose a pump control system wherein an "on"-off" type function can be accomplished with a relatively low power being used as the control signal as opposed to the amount of power that would be required if an ordinary pump was used.

These and other objects will become apparent when the present specification is considered in its entirety along with the presented drawings.

In the present drawings,

FIGURE 1 is a schematic representation of an electromagnetic conductive fluid flow system utilizing a back to back arrangement of pumps in an electromagnetic conductive fluid actuator;

FIGURE 2 is an isometric representation of a typical pump construction;

FIGURE 3 is an electrical schematic of a modulation control system applied to the pumps disclosed in FIGURE 1;

FIGURE 4 is a partial representation of an alternate position of a relay disclosed in FIGURE 3, and;

FIGURE 5 is another schematic representation of a third position for the relay disclosed in FIGURE 3.

The schematically represented system disclosed in FIGURE 1 has a variable volume reservoir chamber 10 formed of any convenient fixed material and is mounted 30 on a base 11. The reservoir chamber 10 is sealed with a bellows 12 that provides the variable volume feature. The bellows 12 is exposed to a low pressure, in the present case disclosed as the atmosphere. The variable volume reservoir chamber is connected by pipe 13 to a control pump 14 that is oriented to pump in the direction of the arrow, that is back into the reservoir chamber. An inlet of the control pump 14 is connected to a pipe 15 to an inlet of power pump 16 which is oriented to pump in the indicated direction away from the control pump 14. The output of the power pump 16 is supplied to a pipe 17 that is in turn connected to an output chamber 20 for output means generally indicated at 19. The power or output chamber 20 is substantially the same as the reservoir chamber 10 in that a fixed wall 21 is provided 40 mounted on a base 22 and the chamber is sealed by a bellows 23. The end of the bellows 23 has a plate 24 attached thereto that in turn is connected to an output shaft 25. A spring 26 is provided to bias the shaft 25 and plate 24 into the uppermost extended condition of the bellows 23. The shaft 25 further passes through an opening 27 in the plate 22 and is capable of moving 50 upon any change in the content of the output chamber of the system.

The entire system described so far is filled with a fluid, preferably of a conductive nature, so that the pumps 14 and 16 can be electromagnetic conductive fluid pumps. The fluid fill normally would be mercury, potassium, sodium, or a mixture of sodium and potassium which is commonly referred to as NaK. The overall system cor-

responds in many details to the electromagnetic pump-actuator device disclosed in Patent 2,948,118 to Carlson et al. In the Carlson et al patent, the use of a single electromagnetic conductive fluid pump and a pair of variable volume chambers is shown as operating a valve which in the present case would be attached to shaft 25.

It is believed that the present description and the information contained in the above referenced issued patent should clearly indicate the application or use of the present system.

In order to better understand the system disclosed in FIGURE 1, a typical electromagnetic conductive fluid pump shown in FIGURE 2, will be described. The

operation of the system in FIGURE 1 can then be more readily understood. A typical electromagnetic conductive fluid pump is formed having a C-shaped magnetic structure 30 which is wound with a coil of wire 31 to supply a magnetic field across a gap 32 in the magnetic structure 30. The gap 32 is formed by two pole faces 33 and 34. It is obvious that the arrangement described will provide a magnetic field of substantial concentration across the gap 32.

A tube 35 of rectangular cross-section is fitted into gap 32 and substantially fills the gap. The tube 35, in a preferred embodiment, would be formed of a high resistance steel so as to be impervious to the conductive fluids that pass through it. The tube 35 has a pair of electrodes 36 and 37 attached to opposite walls thereof so that an electric current can be passed through the tube and the conductive fluid that passes through the tube in a direction mutually perpendicular to the directional flow of the fluid and the magnetic field. It is obvious that this construction provides a conventional electromagnetic conductive fluid pump of the Faraday type and has absolutely no obstructions in the pumping channel. The entire pumping force developed in this type of a unit is due to the interaction of current flowing through the conductive fluid and reacting with a magnetic field. Since this type of unit is well known in the art, it is believed that no further detailed description of the unit is warranted. The supply of current to the electrodes 36 and 37, and the current to the coil 31, can be from any convenient source either of alternating current or of direct current as long as the phase relationship between the current flow and the magnetic field are properly maintained.

Once again considering the system in FIGURE 1, if the pumps 14 and 16 are of the electromagnetic conductive fluid type disclosed in FIGURE 2, it becomes obvious that the passage connecting the reservoir chamber 10 and the output chamber 20 is substantially a continuous open channel with no obstructions that would prevent reverse flow of fluid from the output chamber to the reservoir upon the influence of spring 26 expanding the bellows 23 in an upward direction after the unit has once been compressed by pumping pressure in the direction indicated for pump 16. Thus once pump 16 has been energized to supply a pumping pressure and has compressed the bellows 23, some force must be maintained in the fluid system to retain the system in a stable or fixed state. This ordinarily could be accomplished by the use of a valve, but due to the highly corrosive nature of the electromagnetic conductive fluids used in these systems, the valving is exceedingly difficult and has proved to be impractical. In order to establish a fixed output position for the output chamber 20, it has been discovered that a second pump, pump 14, can be inserted in the system as shown. By energizing the pump 14 in a back to back relationship with the pump 16, it is possible to cut off the flow of fluid to the inlet of pump 16 by energizing the pump 14. If representative values for the various pressures are considered, an explanation of the operation is made much easier.

For example, if the atmospheric pressure of 14.7 pounds per square inch is applied to the reservoir chamber 10 and if pump 14 develops a pressure equal to 14.7 pounds per square inch, it can prevent any fluid from being removed from the reservoir chamber 10. Pump 14, the control pump, is capable of supplying from 0 to 14.7 pounds per square inch, with a relatively small amount of power input. This small amount of power input thus is capable of cutting off all fluid flow to pump 16, a power pump. The power pump is capable of developing any convenient pressure from 0 to as high as 300 pounds per square inch in some systems. A normal system would utilize a pump which develops from 0 to 45 pounds per square inch.

It thus becomes apparent that at any time it is desired to stop the movement of shaft 25 by stopping the com-

pression of bellows 23, it is only necessary to cut off the flow of fluid to pump 16 thereby stalling the pump and the output chamber. This can be accomplished at any time by supplying 14.7 pounds per square inch at the inlet of the power pump in the direction of the control pump 14. At any time it is desired to allow the power pump to continue its operation the control pump is de-energized allowing fluid to flow through it to the power pump thereby allowing an additional supply of fluid to be pumped from the reservoir chamber 10 into the output chamber 20.

With the system just described it is possible to supply a modulation system that is dependent only on a relatively small power input to the control pump. While 15 the total power required may be substantially greater, the amount of power required to control the device is quite small. Since electromagnetic conductive fluid pumps can be built using step down transformers an effective power pump can be readily built but the power pump is quite 20 difficult to control due to the high currents involved in the secondary circuits and the relatively high input powers to the unit as a whole. With the present arrangement it is possible to supply a relatively small control power to the control pump 14 and obtain a system that is effectively locked at any desired position of shaft 25. In 25 order to explain how this would be accomplished, a typical control circuit has been shown in FIGURE 3.

In the control circuit of FIGURE 3 a pair of conventional electric supply lines 40 are shown with 115 volts- 30 60 cycle power available. This can be any convenient source but has been shown as a typical available source for convenience. A step down transformer 41 supplies a low voltage to a resistance bridge of the Wheatstone type. The Wheatstone bridge 42 has three legs which 35 have fixed resistances and are 43, 44, and 45. A fourth leg 46 is a variable resistance which balances or unbalances the bridge 42. The variable resistance 46 could be a temperature sensitive resistance as would be used in a heating control system and would be responsive to a 40 localized ambient temperature. The output of bridge 42 is supplied on conductors 47 and 48 to a conventional amplifier 50. The amplifier 50 is fed to a three position relay 51, which is shown in FIGURE 3 in its center position.

45 A second step down transformer 52 is provided which supplies power to the power pump 16 and the control pump 14 by means of a common conductor 53, and a conductor 54 that passes through contacts 55 and 56 of the three position relay 51. In the position shown in 50 FIGURE 3, the three position relay is supplying power to both the power pump 16 and the control pump 14 at the same time. With this condition existing, in referring back to FIGURE 1, the pump 14 and the pump 16 were both energized. With pump 14 energized and developing 55 a pressure of 14.7 pounds per square inch in the indicated direction, the pump 16 would be receiving no further fluid flow from the reservoir chamber 10. At the same time since pump 16 was not obtaining any fluid it would be able to do nothing further in the way of 60 forcing the bellows 23 to compress and the output shaft 25 would become stationary.

In FIGURE 4 there is shown the relay 51 with its input control conductor 54 and contacts 55 and 56. The contact 55 is open while contact 56 is closed. With this arrangement the control pump would be energized but the power pump would be deenergized. In this arrangement the spring 26 would be expanding bellows 23 and forcing the conductive fluid from the output chamber 20 back into the reservoir chamber 10 with the aid of the pressure developed by the control pump 14. This allows the shaft 25 to return to its upper position.

In FIGURE 5 the relay 51 is disclosed with its input conductor 54 and the contacts 55 and 56. In this case the relay is in its up position and the contact 55 is closed 75 with the contact 56 open. In this condition the power

pump 16 would be energized but the control pump 14 would be deenergized. This would allow the power pump to receive all the fluid that it needs from the reservoir chamber 10 in order to compress the bellows 23 and drive the shaft 25 in a downward direction. It becomes obvious that the various conditions of pumping are thus controlled by the output by the amplifier 50 which is in turn controlled by the condition of the variable resistance 46.

The pump control system that has been specifically described in the present application is only one of many possible embodiments of the present invention. The specific control system disclosed represents one practical approach that utilizes the invention and it is the intent of the present disclosure to show only one means of practicing the entire concept. It is obvious that the back to back pump arrangement disclosed in FIGURE 1 could be utilized in various types of fluid systems for control of various types of devices. The applicant therefore, wishes to be limited in the scope of this invention only by the appended claims.

I claim as my invention:

1. A control system for pump means: fluid reservoir means for supplying a fluid and said reservoir means being exposed to a first pressure; pump means connected to said reservoir means and oriented to pump said fluid into said reservoir means; said pump means being capable of developing a pressure equal to said first pressure; second pump means connected to an inlet of said first pump means and capable of developing a second pressure from said inlet to an outlet of said second pump means; and said second pump means outlet connected to output means having a variable volume in order to transmit variations in volume to a device to be operated; said first pump means controlling the flow of fluid to said second pump means so as to block said second pump means from obtaining said fluid from said reservoir means thereby stalling the flow of fluid to or from said second pump means and stalling said output means.

2. A control system for fluid pumps having a pumping channel not conveniently obstructed to prevent reverse flow upon deenergization of said pumps; a variable volume reservoir chamber for supplying a fluid and said chamber being exposed to a relatively low pressure; a pump connected to said reservoir chamber and oriented to pump said fluid into said chamber; said pump being capable of developing a pressure equal to or greater than said relatively low pressure; a second pump connected to an inlet of said first pump and capable of developing a high pressure from said inlet to an outlet of said second pump; and said second pump outlet connected to an output chamber having a variable volume in order to transmit variations in volume to a device to be operated; said first pump controlling the flow of fluid to said second pump so as to block said second pump from obtaining said fluid from said reservoir chamber thereby stalling the flow of fluid to or from said second pump and stalling said output chamber.

3. A control system for electromagnetic conductive fluid pump means having a continuously unobstructed pumping channel not conveniently obstructed to prevent reverse flow upon deenergization of said pump means; reservoir means for supplying a conductive fluid and said reservoir means being exposed to a first pressure; electromagnetic conductive fluid pump means connected to said reservoir means and oriented to pump said fluid into said reservoir means; said pump means being capable of developing a pressure equal to said first pressure; second electromagnetic conductive fluid pump means connected to an inlet of said first pump means and capable of developing a second pressure from said inlet to an outlet of said second pump means; and said second pump outlet connected to an output means having a variable volume in order to transmit variations in volume to a device to be operated; said first pump means controlling the flow of fluid to said second pump means so as to block said second

pump means from obtaining said fluid from said reservoir means thereby stalling the flow of fluid to or from said second pump means and stalling said output means.

4. A control system for electromagnetic conductive fluid pumps having a continuously unobstructed pumping channel not conveniently obstructed to prevent reverse flow upon deenergization of said pumps; a conductive fluid reservoir chamber for supplying a conductive fluid; said chamber being variable in volume and being exposed to a relatively low pressure; an electromagnetic conductive fluid pump connected to said reservoir chamber and oriented to pump said fluid into said chamber; said pump being capable of developing a pressure equal to or greater than said relatively low pressure; a second electromagnetic conductive fluid pump connected to an inlet of said first pump and capable of developing a high pressure from said inlet to an outlet of said second pump; and said second pump outlet connected to an output chamber having a variable volume in order to transmit variations in volume to a device to be operated; said first pump controlling the flow of fluid to said second pump so as to block said second pump from obtaining said fluid from said reservoir chamber thereby stalling the flow of fluid to or from said second pump and stalling said output chamber.
5. A control system for liquid metal pumps having a pumping channel not conveniently obstructed to prevent reverse flow upon deenergization of said pumps; a reservoir chamber for supplying a liquid metal; said chamber being variable in volume and being exposed to a relatively low ambient pressure, normally the atmosphere; a liquid metal pump connected to said reservoir chamber and oriented to pump said liquid metal into said chamber; said pump being capable of developing a pressure equal to or greater than said relatively low pressure; a second liquid metal pump connected to an inlet of said first pump and capable of developing a high pressure from said inlet to an outlet of said second pump; and said second pump outlet connected to an output chamber having a variable volume in order to transmit variations in volume to a device to be operated; said first pump controlling the flow of liquid metal to said second pump so as to block said second pump from obtaining said liquid metal from said reservoir chamber thereby stalling the flow of liquid to or from said second pump and stalling said output chamber.
6. A modulation system for pumps; condition responsive means having three electrical output conditions; a variable volume reservoir chamber for supplying a fluid and said chamber being exposed to a first pressure; a pump connected to said reservoir chamber and oriented to pump said fluid into said chamber upon either said first or said second electrical output conditions being connected to said pump; said pump being capable of developing a pressure equal to said first pressure; a second pump connected to an inlet of said first pump and capable of developing a high pressure from said inlet to an outlet of said second pump upon either said second or said third electrical output conditions being connected to said second pump; and said second pump outlet connected to an output chamber having a variable volume in order to transmit variations in volume to a device to be operated; said first pump controlling the flow of fluid to said second pump in response to said condition responsive means.
7. A modulation system for electromagnetic conductive fluid pumps having a continuously unobstructed pumping channel not conveniently obstructed to prevent reverse flow upon deenergization of said pumps; condition responsive means having three electrical output conditions; a conductive fluid reservoir chamber for supplying a conductive fluid; said chamber being variable in volume and being exposed to a low pressure; an electromagnetic conductive fluid pump connected to said reservoir chamber and oriented to pump said fluid into said chamber upon either said first or said second electrical output conditions being connected to said pump; said pump being capable

of developing a pressure equal to said low pressure; a second electromagnetic conductive fluid pump connected to an inlet of said first pump and capable of developing a high pressure from said inlet to an outlet of said second pump upon either said second or said third electrical output conditions being connected to said second pump; and said second pump outlet connected to an output chamber having a variable volume in order to transmit variations in volume to a device to be operated; said first pump con-

trolling the flow of fluid to said second pump so as to block said second pump from obtaining said fluid from said reservoir chamber thereby stalling the flow of fluid to or from said second pump and stalling said output chamber in response to said condition responsive means second electrical output condition.
